UNITED STATES PATENT OFFICE.

CHARLES R. DICKINSON, OF SEATTLE, WASHINGTON.

COMBINED COLLAR-FASTENER AND TIE-SUPPORTER.

1,286,556.

Specification of Letters Patent.

Patented Dec. 3, 1918.

Application filed December 5, 1916. Serial No. 135,114.

To all whom it may concern:

Be it known that I, CHARLES R. DICKINSON, a citizen of the United States, residing at Seattle, in the county of King and State 5 of Washington, have invented certain new and useful Improvements in Combined Collar-Fasteners and Tie-Supporters; and I do hereby declare the following to be a full, clear, and exact description of the invention, 10 such as will enable others skilled in the art to which it appertains to make and use the same.

This invention relates to a combined collar fastener and tie supporter and has for 15 one of its objects, the provision of a device of this character, which will receive a necktie and support the same and which will secure the collar to a shirt band.

Another object of this invention is to provide a split body for receiving a necktie that 20 will support it properly in relation to the collar and having means thereon for attaching it to a shirt band.

A further object of this invention is to 25 provide means for attaching a body both to the collar and to the shirt band.

A still further object of this invention is the provision of a combined collar fastener and tie supporter of the above stated character, 30 which shall be simple, durable and efficient and which may be manufactured and sold at a comparatively low cost.

With these and other objects in view, as 35 will become more apparent as the description proceeds, the invention consists in certain novel features of construction, combination and arrangement of parts as will be hereinafter more fully described and claimed.

40 For a complete understanding of my invention, reference will be had to the following description and accompanying drawings, in which:

Figure 1 is a rear elevation of a combined 45 fastener and tie supporter constructed in accordance with my invention,

Fig. 2 is a fragmentary vertical sectional view of a collar and shirt band illustrating my invention applied thereto,

50 Fig. 3 is a fragmentary perspective view of a modified form of a combined collar fastener and tie supporter,

Fig. 4 is a fragmentary vertical sectional view of a collar and shirt band illustrating

ing my modified form of invention applied 55 thereto,

Fig. 5 is a perspective view of a third modified form of my invention, illustrating means of attaching the body portion to a collar employing an attaching tab, 60

Fig. 6 is a fragmentary vertical sectional view of a collar and shirt band illustrating another modified form of a combined collar fastener and tie supporter applied thereto,

Fig. 7 is an elevational view of another 65 modified form of my invention, illustrating means for securing the attaching tab of a collar thereto,

Fig. 8 is a fragmentary sectional view of a collar and shirt band illustrating the last 70 mentioned modified form of my invention applied thereto,

Fig. 9 is a fragmentary plan view of a collar illustrating the attaching tab applied 75 thereto,

Fig. 10 is an end elevation of a modified form of a combined collar fastener and tie supporter,

Fig. 11 is a perspective view of another modified form of a combined collar fastener 80 and tie supporter constructed from a continuous length of wire, and

Fig. 12 is a perspective view of a modified form of my invention, illustrating it constructed from a continuous length of wire. 85

Referring in detail to the drawings, the numeral 1 indicates an elongated body for receiving a necktie 2 and the body 1 is preferably in my preferred form constructed from a single length of sheet metal, which is 90 bent back upon itself to form an elongated loop, for the purpose of receiving the necktie 2. One end of the strip of metal is offset as illustrated at 3 to receive the other end of the strip of metal providing an opening in 95 the body for the purpose of allowing a necktie to be inserted therein.

The body 1 is placed between the outer wall 5 and the inner wall 6 of a collar 7 and has formed thereon adjacent its lower rear end a shank 8 to which a pair of arms 9 and 10 are pivoted. The pivot connection between the arms 9 and 10 and the shank 8 is of a semi-ratchet nature, that is to substantially lock the arms 9 and 10 in a vertical position and also to lock them in a horizontal position. The arm 9 being of a smaller size than the arm 10 will be received within 105

the arm 10 when said arms are in a horizontal position. When in this horizontal position, the arms are adapted to be inserted through the button hole of the rear wall 6 of the collar 7 and then swung upon their pivots to a vertical position, as illustrated in Fig. 2, thus locking or sufficiently securing the body 1 between the inner and outer walls 5 and 6 of the collar 7.

10 A substantially L-shaped attaching arm 11 is pivotally secured to the lower end of the body 1 as illustrated at 12. This pivot connection is of a ratchet nature and the arm portion 13 of the attaching arm 11 is received within a pocket 14 of a shirt band 15, thus securing the collar 7 to the shirt band 15.

15 The arm portion 16 of the substantially L-shaped attaching arm 11 is of sufficient length for accommodating the inner wall 6 of the collar 7 and the thickness of the outer wall of the pocket 14 of the shirt band 15 so as to provide a substantially close fit between the collar 7 and the shirt band 15.

20 25 In operation, the necktie 2 is placed within the body 1 by inserting the necktie between the ends of the metallic strip which forms the body and the substantially L-shaped attaching arm 11 is swung downward from the body 1 to allow the arms 9 and 10 to be swung to a horizontal position. When the arms 9 and 10 are in a horizontal position, they are inserted through the button hole of the rear wall 6 of the collar 7 so 30 35 that the body 1 will be properly positioned between the outer and inner walls of the collar. The arms 9 and 10 are then swung upon their pivots in opposite directions to dispose them in a vertical plane and engaging the inner wall 6 of the collar, thus locking the body between the inner and outer walls of the collar. The substantially L-shaped attaching arm then is swung upon its pivot and the arm portion 13 is inserted within the 40 45 pocket 14 of the shirt band 15, thus the necktie is properly supported within the collar and the collar efficiently secured to the shirt band.

50 Referring to my modified form of invention disclosed in Figs. 3 and 4, it consists of an elongated body 17 which is constructed preferably from sheet metal being bent back upon itself to form a loop, the lower end of the strip of metal being offset inwardly as 55 illustrated at 18 to receive the other end of the strip of metal so that a necktie may be inserted between the ends of the strip of metal to enter within the body 17.

60 A plate 19 has its ends 20 and 21 bent at right angles. The end 20 is bent to extend in an opposite direction from the end 21 and is secured to the rear wall of the body 17 in any well known manner. The body 17 is placed between the outer wall 22 and the inner wall 23 of a collar 24 and the plate 19 is

inserted through the button hole of the inner wall 23 so that the right angled end 20 is normally positioned within the button hole as clearly illustrated in Fig. 4.

65 A substantially U-shaped attaching arm 25 is pivotally secured to the right angled end 21 of the plate 19 as illustrated at 26. This pivot connection is of the ratchet nature so that the locking arm 25 may be substantially locked in a vertical position as 70 illustrated in Fig. 3, or it may be swung to a substantially horizontal position and held in the last mentioned position by the ratchet of the pivot 26. When in this last mentioned position, the attaching arm 25 may be readily 75 passed through the button hole of the inner wall 23 of the collar 24 and then swung to a vertical position as illustrated in Fig. 3 and inserted upwardly within a pocket 27 of a shirt band 28 to secure the collar 24 to the 80 85 shirt band 28.

90 Referring to my modified form of invention disclosed in Fig. 5, it consists of an elongated body 29, which is constructed from a single length of sheet metal which is bent back upon itself to form a loop for the purpose of receiving a necktie, the lower end of the metal strip is offset inwardly as illustrated at 30 to receive the other end of the metal strip to provide an opening to the 95 loop of the body for receiving a necktie. The rear wall of the body 29 is bent back upon itself as illustrated at 31 to form a hinge or pivot 32 for receiving a wire attaching loop 33 of an elongated construction. 100 The foregoing description relates to a form of combined collar fastener and tie supporter used in connection with a collar as illustrated in Fig. 9, the numeral 34 indicating the inner wall of the collar and having secured thereto an attaching tab 35 to take the place of the ordinary button hole within the inner wall of a collar. The body 29 is placed between the inner and outer walls of the collar and the wire loop 33 is 105 passed under the lower edge of the inner wall 34 so that the tab 35 may depend downwardly therethrough. The tab 35 is then bent upwardly and received within the pocket of a shirt band, thus the body 29 is secured within the inner and outer walls of the collar and the collar is secured by the tab to the shirt band. 110 115

120 Referring to my modified form of invention as shown in Fig. 6, it consists of an elongated body 36 which is similar in construction to the body 17 and has secured thereto a plate 37 which is inclined downwardly and in the direction of the rear wall of the body 36 as clearly illustrated in Fig. 6 and has its lower end bent upwardly upon itself to form an attaching arm 38 to be received within a pocket 39 of a shirt band 40. The body 36 is placed between the inner and outer walls of the collar 41 and the 130

attaching end of the plate 37 to the body is received within the button hole of the inner wall of the collar 41 and the lower end of the plate 37 is clamped to the inner walls of the collar against the body so as to prevent accidental displacement of the body within the collar. The attaching arm 38 is then inserted upwardly within the pocket 39 of the shirt band 40, thus efficiently supporting the necktie within the collar 41, whereby said collar may also be secured to the shirt band of a shirt.

Referring to my modified form of invention as disclosed in Figs. 7 and 8 it consists of an elongated body 42 constructed from sheet metal which is bent back upon itself to form a looped body and the upper end of said strip is offset outwardly as illustrated at 43 to receive the lower end of the strip whereby a necktie may be inserted within the body. A substantially L-shaped attaching arm 44 is pivotally secured to the lower end of the body 42 as illustrated at 45. The pivot connection between the arm 44 and the body is of a ratchet construction so that said arm may be substantially locked in several positions. The arm portion 46 of the substantially L-shaped arm 44 is provided with a pair of relatively spaced and transversely extending slots 47. The body 42 is placed between the inner and outer walls of a collar of the type disclosed in Fig. 9 and the attaching tab 35 is passed downwardly through one of the slots 47 and upwardly through the other slot as illustrated in Fig. 8 so as to secure the collar to the body and the substantially L-shaped attaching arm is then inserted within a pocket 48 of a shirt band 49.

Referring to my modified form of invention as disclosed in Fig. 10, it consists of an elongated body 50 similar in construction to the body 42 and has pivotally secured thereto a substantially L-shaped attaching arm 51 adapted to be received within a pocket of a shirt band. The pivot connection between the attaching arm 51 and the body 50 is of the ratchet construction so as to substantially lock the attaching arm 51 in several positions. An arm 52 is pivotally secured to the rear wall of the body 50 as illustrated at 53. The pivot connection between the arm 52 and the body 50 is of a ratchet construction so that the arm 52 may be substantially locked into a horizontal position and also in a downwardly depending position. When the body 50 is placed between the inner and outer walls of a collar, the attaching arm 51 is swung downwardly and the arm 52 is swung into a horizontal position so that the same may be readily passed through the button hole of the inner wall of the collar and then swung downwardly to permanently secure the body within the collar. The attaching arm 51 is

then swung upwardly and positioned within the pocket of a shirt band, thus, the collar is permanently secured to the body 50 and to the shirt band of a shirt.

Referring to my modified form of invention as disclosed in Fig. 11, it consists of a body 54 and an attaching arm 55, which are constructed from a single length of wire. The wire is first bent to form the attaching arm 55 and then the body 54. The portion 56 between the body and the attaching arm is of sufficient length to accommodate the width of the inner wall of a collar. The portion 57 of the attaching arm is inclined in the direction of the body to cause a clamping action upon the inner wall of the collar, thus, permanently securing the body between the inner and outer walls of a collar, so as to support a necktie.

The bodies disclosed in Figs. 1 to 10 have their side portions concaved to conform to the contour of the walls of the collar so that the bodies may readily adjust themselves within the collar without bulging the side walls of said collar.

Referring to my modified form of invention as disclosed in Fig. 12, it consists of a combined collar fastener and tie supporter constructed from a continuous length of wire. The wire is first bent to form an elongated loop member 58 to receive the tab 35 of the collar 34. One end of the wire is bent to extend vertically and downwardly upon itself to form a portion of a tie receiving body 58', the end of which is bent in loop formation as illustrated in Fig. 12. The other end of the wire after forming the loop member 58 is twisted about the before-mentioned end of the wire as illustrated at 60 and is bent downwardly and upwardly as illustrated at 61 to form the remaining portion of the body 58'. The ends of the wires are each looped so as to provide a smooth surface to the end, whereby the necktie may be readily inserted within the body 58'.

While I have shown and described the preferred embodiment of my invention, it will be understood that minor changes in construction, combination and arrangement of parts may be made without departing from the spirit and scope of the invention as claimed.

Having thus described my invention, what I claim is:

1. A combined collar fastener and necktie supporter comprising a body for receiving a necktie, means for securing the body to a collar, a locking arm pivoted to the body and received within the pocket of a neck band of a shirt, and means pivoted to the body and extending through the button hole of a collar for securing the body to said collar.

2. A combined collar fastener and necktie

- supporter comprising a body for receiving a necktie, a ratchet hinge formed on said body, a substantially L-shaped attaching arm secured to the ratchet hinge and received within the pocket of a neck band of a shirt, an arm hinged to said body and extending through the button hole of the collar to secure the body to said collar. 3. A combined collar fastener and necktie supporter comprising a body for receiving a necktie, means for securing said body to the neck band of a shirt, a shank formed on said body and extending through the button hole of a collar, a pair of arms hinged to said shank and adapted to extend in opposite directions to secure the body to the collar. 4. A combined collar fastener and tie supporter comprising a body in the form of an elongated split loop having its free ends arranged in overlapping and abutting engagement, and securing means carried by the body. 5. A combined collar fastener and tie supporter comprising a body in the form of an elongated split loop having its free ends arranged in overlapping abutting engagement, one end being slightly offset to receive the other end, and securing means carried by the body for securing it to a collar and shirt band. In testimony whereof I affix my signature in presence of two witnesses.

CHARLES R. DICKINSON.
